PLASTIC CURTAIN

William Z. Salcer, Rego Park, N.Y., assignor to B. & S. Plastic Art, Inc., Jersey City, N.J., a corporation of New Jersey

Filed Oct. 17, 1962, Ser. No. 72,149

Term of patent 7 years

(Cl. D92—26)

The FIGURE is a plan view of a portion of a plastic curtain showing my new design.

A complete design unit, comprising one half of a complete curtain, is shown above the broken line, and this unit is reproduced in the other half of the curtain.

The section disclosed is shown over a dark background to bring out the details of the design.

I claim:

The ornamental design for a plastic curtain, as shown and described.
